(57) **CLAIM**

The ornamental design for a battery clamp, as shown and described.

DESCRIPTION

FIG. 1 is a front perspective view of an inner part of a new design for a battery clamp;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front perspective view of the inner part of FIG. 1, fitted with an exterior part of the assembled battery clamp;

FIG. 9 is a left side elevational view thereof;

FIG. 10 is a right side elevational view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a perspective view of the inner part of the battery clamp shown in FIG. 1, a cable, and a nut for connecting the battery clamp and cable together;

FIG. 16 is another perspective view of the inner part of the battery clamp shown in FIG. 1, a cable, and a nut for connecting the battery clamp and cable together; and,

FIG. 17 is a perspective view of the inner part of the battery clamp shown in FIG. 1, a cable, and a nut for connecting the battery clamp and cable together.

The broken lines shown represent portions of the battery clamp that form no part of the claimed design.

1 Claim, 17 Drawing Sheets
